UNITED STATES PATENT OFFICE.

GEORGE G. SEHER, OF PHILADELPHIA, PENNSYLVANIA.

DESIGN FOR A GRIPPING DEVICE.

59,936.

Specification for Design.

Patented Dec. 6, 1921.

Application filed May 14, 1920. Serial No. 381,482. Term of patent 3½ years.

To all whom it may concern:

Be it known that I, GEORGE G. SEHER, a citizen of the United States, residing at Philadelphia, in the county of Philadelphia and State of Pennsylvania, have invented a certain new, original, and ornamental Gripping Device, of which the following is a specification, reference being had to the ac-

companying drawings, forming a part thereof.

The figure is a perspective view of the gripping device.

I claim;

The ornamental design for a gripping device as shown.

GEORGE G. SEHER.
